(57) **CLAIM**

The ornamental design for a drain clog remover tool, as shown and described.

DESCRIPTION

FIG. 1 is a perspective view of a drain clog remover tool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the drain clog remover tool;

FIG. 10 is another exploded perspective view of the drain clog remover tool;

FIG. 11 is an enlarged perspective view of a handle of the drain clog remover tool shown separately for ease of illustration;

FIG. 12 is a rear elevational view thereof;

FIG. 13 a top plan view thereof;

FIG. 14 is an enlarged view of portion 15 shown in FIG. 2, and,

FIG. 15 is an enlarged view of portion 15 shown in FIG. 2. The drain clog remover tool is shown with symbolic breaks in its length and the appearance of any portion of the drain clog remover tool between the break lines form no part of the claimed design. The dash-dash broken lines in the drawings depict portions of the drain clog remover tool that form no part of the claimed design. The dot-dash broken

(Continued)

lines represent boundaries of the enlarged portions and form no part of the claimed design.

1 Claim, 15 Drawing Sheets
